UNITED STATES PATENT OFFICE.

CASPAR HERMANN, OF LEIPZIG-GROSS-ZSCHOCHER, GERMANY, ASSIGNOR OF ONE-HALF TO GEORG RICHTER, OF LEIPZIG, GERMANY.

ROTARY PRINTING-MACHINE.

1,091,841.

Specification of Letters Patent. Patented Mar. 31, 1914.

Application filed March 8, 1913. Serial No. 752,941.

To all whom it may concern:

Be it known that I, CASPAR HERMANN, of Leipzig-Gross-Zschocher, Kingdom of Saxony, German Empire, a citizen of the United States of North America, and whose post-office address is 19 Kirchstrasse, Leipzig-Gross-Zschocher, Kingdom of Saxony, German Empire, have invented new and useful Improvements in or Relating to Rotary Printing-Machines, of which the following is a specification.

This invention relates to rotary printing machines with two cylinders for indirect lithographic printing and has for its object to extend the field of application of such machines by enabling indirect lithographic printing to be done not only on flexible sheets of paper, fabric and thin metal plates, but also on rigid metal plates and cardboard sheets.

Rotary machines for indirect lithographic printing with only two cylinders are already well known, but sheets printed on them are carried around the small cylinder provided with elastic covering and laid on the delivery "rake" with the printed face downward. Apart from the fact that the latter circumstance is liable to lead to smudging, it is impossible in the said well known machine to print thick rigid metal plates or sheets of cardboard which must not be bent. In order to attain the result mentioned above, the machine according to this invention is characterized by the large cylinder carrying the form plate and an elastic counter-pressure covering being provided with grippers so arranged that the sheets fed between the cylinders are delivered flat with the printed faces upward. Consequently, as already stated, it is possible to print rigid thick metal plates and cardboard sheets in the same machine as flexible paper sheets, metal plates and fabric. As moreover in this machine the large cylinder, in addition to the form plate, is provided with an elastic counter-pressure covering, a further advantageous use of the same machine is possible as, according to this invention, the small cylinder is provided with a color doctor that can be lifted off, and the rubber covering of the small cylinder can be exchanged for a copper plate. In that case one and the same machine can be used for printing paper sheets and fabric by the intaglio process, the

sheets again being delivered with the printed face upward.

The accompanying drawing shows diagrammatically a construction of the machine according to this invention.

In the said drawing *a* is the large cylinder covered with a metal form plate (zinc plate) *b*, as well as with an elastic counter-pressure covering *c*. The moistening device is marked *d* and the inking device *e*, both being capable of being lifted off in the well known manner. The cylinder *a* is provided within the elastic counter-pressure covering *c*, with ledges *f* by means of which the "putting on" rollers are forced off when the elastic covering passes in front of the inking device and the moistening device. Moreover, the cylinder *a* carries grippers *g* and on the delivery side stripping-off fingers *h* are provided. The feed table is marked *i* and the support for the stack of printed sheets or plates is marked *k*. The small cylinder *l* is provided with an elastic covering *m*, and next to the same is arranged an inking device *n* that can be lifted off and a doctor *o*. A guide roller *p* which can be slightly raised and lowered relatively to the large cylinder *a*, is used in the position of engagement, for guiding when paper sheets and fabrics are printed, while in printing thick metal plates and cardboard sheets, it is lifted off. If indirect lithographic printing is to be done, the color doctor is lifted off, the small cylinder provided with elastic covering and the large cylinder with the zinc plate. The latter is moistened by the moistening apparatus and inked by the inking device, and during the rotation of the large cylinder, transfers to the elastic covering of the small cylinder *l* which is then printed off on the sheet or plate seized by the gripper *g* between the two elastic coverings of the large and small cylinders. Shortly before the stripping-off fingers *h* act, the gripper releases the sheet or plate, and the latter is guided in a straight line, with the printed face upward, on to the delivery table. As shown in the drawing, no bending of the sheets or plates around the cylinder takes place in the said machine.

If the machine is to be used as an intaglio printing machine, it is merely necessary to remove the zinc plate of the large cylinder, to lift off or disengage the moistening ap-

paratus and the inking device of the same and to bring into engagement the inking device and color doctor of the small cylinder after its elastic covering has been exchanged for a non-elastic covering such as a copper plate either etched or prepared in some other manner for intaglio printing.

What I do claim as my invention, and desire to secure by Letters Patent of the United States, is:—

1. A rotary printing machine comprising the combination with a large cylinder having grippers and an elastic impression surface and adapted to receive a form plate; of a small cylinder adapted to receive interchangeably an elastic transfer surface for indirect lithographic printing from the form plate of said large cylinder or an intaglio printing surface for intaglio printing when said form plate is omitted from said large cylinder.

2. A rotary printing machine comprising the combination with a large cylinder having grippers and an elastic impression surface and adapted to be provided with a form plate; of a small cylinder adapted to interchangeably receive an elastic transfer surface for lithographic printing from said form plate or an intaglio printing surface for intaglio printing when said form plate is omitted, and means for stripping off the printed sheets on the delivery side of the printing couple thus constituted.

3. A rotary printing machine comprising the combination with a large cylinder having grippers and an elastic impression surface and adapted to receive a form plate; of a small cylinder adapted to interchangeably receive an elastic transfer surface for litho-

graphic printing from said form plate or an intaglio printing surface for intaglio printing when said form plate is omitted and disengageable inking and moistening devices for said form plate.

4. A rotary printing machine comprising the combination with a large cylinder provided with grippers and an elastic impression surface and adapted to receive a form plate; of a small cylinder adapted to receive interchangeably an elastic transfer surface for lithographic printing from said form plate or an intaglio printing surface for intaglio printing when said form plate is omitted, disengageable moistening and inking devices for said large cylinder and an independent disengageable inking device having a color doctor for said smaller cylinder.

5. A rotary printing machine comprising the combination with a large cylinder having grippers and an elastic printing surface and adapted to receive a form plate; of a smaller cylinder adapted to interchangeably receive an elastic transfer surface for lithographic printing from said form plate or an intaglio printing surface for intaglio printing when said form plate is omitted, and a guide roller movable into operative position on the delivery side of the printing couple thus constituted.

In testimony whereof I have hereunto set my hand in presence of two subscribing witnesses.

CASPAR HERMANN.
